PIPE WRENCH WITH LINKED GRIPPING MEANS

Allen B. Wilson, Galena Park, Tex.

Application September 8, 1949, Serial No. 114,486

1 Claim. (Cl. 81—57)

1. This invention relates to rotary wrenches.

An object of this invention is to provide a powered wrench for clamping engagement about a pipe or other round object, whereby the article engaged with the wrench may be rotated, and the gripping force will proportionately increase with rotation of the article and with increase in the torsional strain thereon.

Another object of this invention is to provide a powered wrench which can be easily clamped about the article between the ends of the latter, and can be used for turning the article in either direction.

A further object of this invention is to provide a rotary wrench in which the motor is mounted in the handle or if desired a flexible drive shaft may be connected to the wrench.

With the above and other objects in view, my invention consists in the arrangement, combination and details of construction disclosed in the drawings and specification, and then more particularly pointed out in the appended claim.

In the drawings,

Figure 1 is a plan view, partly broken away and in section, of a rotary wrench constructed according to an embodiment of this invention,

Figure 2 is a fragmentary sectional view taken on the line 2—2 of Figure 1,

Figure 3 is a fragmentary sectional view taken on the line 3—3 of Figure 2,

Figure 4 is a fragmentary sectional view taken on the line 4—4 of Figure 1.

Referring to the drawings, the numeral 10 designates generally a handle which is of tubular construction and is provided at its rear end with one or more ears 11, having an opening 13 therethrough, by means of which the handle may be anchored or secured to a stationary element.

The forward end of the handle 10 has rockably secured thereto an arcuate member 12 which is mounted on a pivot 14. A bolt 15 is threaded through an ear 16 carried by the handle 10 and is adapted to bear against the arcuate member 12 on the rear side thereof so as to limit the rocking of arcuate member 12 with respect to the handle 10.

The arcuate member 12 has extending therefrom pivotally connected link members 17 and 18, with the last member 17a adapted to be releasably connected to the adjacent end of the arcuate member 12 as will be hereinafter described.

The links 18 have rotatably mounted therein friction rollers 19 and the arcuate member 12 has mounted in the inner concave side thereof

friction rollers 20 which are adapted to engage the periphery of a pipe or work piece 21. Gears 22 are fixed to the shafts 23 on which the rollers 19 are fixedly mounted, and gears 22 mesh with intermediate gears 24 mounted on shafts 25 carried by the links 17.

A pair of latching hooks 26 are rockably mounted on pins 27 which are carried by a U-shaped latch operating member 28. The latch operating member 28 is rockably mounted on an adjacent gear roller shaft 23 and the latch operating member 28 includes a handle or U-shaped bar 29 projecting outwardly therefrom. A pair of latch pins 30 are secured to a pair of links 31 which are formed with elongated arcuate slots 32 within which the adjacent ends of shafts 23 and 25 are adapted to loosely engage. The inner end of the links 31 engage about pivot members 33 carried by ears or straps 34 which are fixed relative to the handle 10 so that when the arcuate member 12 rocks on the pivot member 14 under frictional contact of the rollers 20 with the work piece 21, links 31 will be moved to the right, as viewed in Figure 1, so as to thereby more firmly tighten the chain about the work piece 21, depending on the torsional resistance of the work piece 21.

The several rollers 20 are rotated by means of a motor or power member 35 or through a flexible drive means (not shown) which is mounted in a housing 36 carried by the rear of the handle 10. A motor shaft 37 extends from the motor 35 and has a worm 38 secured thereto or formed integral therewith. The shaft 37 engages through bearings 39 and 40 which are carried by the handle 10, and worm 38 meshes with a worm gear 41 which is mounted on a transversely disposed shaft 42. The shaft 42 also has fixed thereon a spur gear 43 which meshes with an intermediate spur gear 44 rotatably mounted on the pivot member 14 and intermediate gear 44 meshes with the adjacent roller gear 22 which is carried by the arcuate member 12.

In the use and operation of this device, the chain shaped head of the wrench is engaged about the pipe or work piece 21, the latch operator 28 being initially pulled outwardly so as to move the latch hooks 26 forwardly by reason of the eccentrically mounted pins 27 carried by the operator 28. When the operator 28 is moved inwardly to

the position shown in Figure 1, the latch members or hooks 26 which are engaged with the pins 30 will draw the chain tightly about the work piece 21 so that the friction rollers 19 will firmly engage the periphery of the pipe or work piece 21.

The motor 35 may then be operated so that the

several friction rollers 19 and 20 will be rotated through the gear train hereinbefore described, to rotate the work piece or pipe 21 in the desired direction. It will be understood that the wrench may be used for threading or unthreading pipes as the wrench is merely turned over when a reverse movement is desired.

In the event the latch members 26 do not provide for the firm contact of the rollers 19 and 20 with the work piece, the adjusting bolt 15 may be loosened so that the arcuate member 12 may rock counterclockwise with respect to the handle 10 and thereby cause the link 31 to move to the right and effect a contraction of the circle formed by the links 17 and 18 and the arcuate member 12.

The construction of housing links 17 and 18 permits the chain to open only enough to slip the open section of the wrench over the work piece. This will facilitate putting on and taking off the wrench.

I do not mean to confine myself to the exact details of construction herein disclosed, but claim all variations falling within the purview of the appended claim.

What I claim is:

A rotary wrench comprising a handle, a work encircling chain carried by said handle, said chain

including a relatively long arcuate link pivotally secured to said handle and constituting one end of said chain, releasable latch means connecting the other end of said chain with said handle, friction rollers carried by said chain, a gear train connecting said rollers together, a pair of forwardly projecting arms carried by said handle, an arcuate link pivotally connected at one end thereof to each arm, a keeper pin carried by the opposite end of each link and engageable by said latch means, torsional pull of said rollers in one direction effecting rocking of said handle relative to said long link in a direction to effect contraction of said chain about the work, and adjustable means limiting the rocking of said handle relative to said long link.

ALLEN B. WILSON.
